RECORD SHEET FOR SOCIAL SECURITY OR THE LIKE DATA

Collie James Cotton and Dorothy L. Cotton,
Ansted, W. Va.

Application August 8, 1952, Serial No. 20,958

Term of patent 14 years

(Cl. D59—2)

To all whom it may concern:

Be it known that we, Collie James Cotton and Dorothy L. Cotton, citizens of the United States, residing at Ansted, county of Fayette, State of West Virginia, have invented a new, original, and ornamental Design for a Record Sheet for Social Security or the like Data, of which the following is a specification, reference being had to the accompanying drawing, forming a part hereof.

The figure is a plan view of a record sheet for social security or the like data, showing our new design, the sheet being of no appreciable thickness.

We claim:

The ornamental design for a record sheet for social security or the like data, as shown and described.

COLLIE JAMES COTTON.
DOROTHY L. COTTON.
